RADIATION METER

William R. Polye, River Edge, and George V. Zito, South Hackensack, N. J., assignors, by mesne assignments, to the United States of America as represented by the United States Atomic Energy Commission

Application January 31, 1950, Serial No. 7,611

Term of patent 14 years

(Cl. D52—1)

To all whom it may concern:

Be it known that we, William R. Polye and George V. Zito, citizens of the United States, residing at River Edge, county of Bergen, State of New Jersey, and South Hackensack, county of Bergen, State of New Jersey, respectively, have invented a new, original, and ornamental design for a Radiation Meter, of which the following is a specification reference being had to the accompanying drawings, forming a part hereof.

Figure 1 is a perspective view of a radiation meter embodying the new design.

Figure 2 is a top view of the radiation meter.

Figure 3 is a front view of the radiation meter.

Figure 4 is a bottom view of the radiation meter.

We claim:

The ornamental design for a radiation meter, as shown.

WILLIAM R. POLYE.
GEORGE V. ZITO.
